United States Patent Office

Des. 180,183

Patented Apr. 30, 1957

180,183

COUCH

Robert A. Gera, Elmhurst, Ill., assignor to International Furniture, Division of Schnadig Corp., Chicago, Ill., a corporation of Delaware

Application May 14, 1956, Serial No. 41,489

Term of patent 3½ years

(Cl. D15—11)

Figure 1 is a perspective view of the couch;

Figure 2 is an end elevation of the couch viewed from the armless end thereof;

Figure 3 is a top plan view of the couch;

Figure 4 is a front view in elevation; and

Figure 5 is an end elevation of the couch viewed from the end opposite from that shown in Figure 2.

I claim:

The ornamental design for a couch, substantially as shown.
